UNITED STATES PATENT OFFICE.

MATHEW P. EMBACH AND JOHN L. BRUCE, OF HOLDENVILLE, OKLAHOMA.

DOOR-FASTENER.

1,335,100.

Specification of Letters Patent. Patented Mar. 30, 1920.

Application filed March 31, 1917. Serial No. 158,907.

To all whom it may concern:

Be it known that we, MATHEW P. EMBACH and JOHN L. BRUCE, citizens of the United States, residing at Holdenville, in the county of Hughes and State of Oklahoma, have invented certain new and useful Improvements in Door-Fasteners, of which the following is a specification, reference being had to the accompanying drawings.

10 This invention relates to certain improvements in door fasteners and has relation more particularly to a device of this general character especially designed and adapted for use in connection with screen doors or the like; and it is an object of the invention to provide a fastener of this general character having novel and improved means whereby the same will automatically engage a screen door or the like and effectively maintain the same in closed position but offer no undue hindrance to the opening of the screen door when the requirements of practice necessitate.

15 The invention consists in the details of construction and in the combination and arrangement of the several parts of our improved door fastener whereby certain important advantages are attained and the device is rendered simpler, less expensive and 20 otherwise more convenient and advantageous for use, all as will be hereinafter more fully set forth.

25 The novel features of the invention will hereinafter be definitely claimed.

30 35 In order that our invention may be the better understood, we will now proceed to describe the same with reference to the accompanying drawings, wherein—

40 Figure 1 is a view in perspective of a door fastener constructed in accordance with an embodiment of our invention; and

45 Fig. 2 is a sectional view illustrating our improved fastener applied and maintaining a screen door or the like in closed position.

50 As disclosed in the accompanying drawings, 1 denotes a door rabbet produced in a door jamb J and with which coacts the door D, preferably a screen door.

55 Our improved fastener comprises an elongated strip 2 of sheet metal adapted to be secured to a side wall of the rabbet 1 in any conventional manner but preferably through the medium of the screws 3 or other headed members disposed through

the openings 4 produced in the strip 2 adjacent the opposite ends thereof.

Extending laterally from an edge of the strip 2 and at substantially its longitudinal center is an elongated tongue 5 having its outer or free portion returned, as at 6. The returned portion 7 is of such a length as to have its free end terminate in close proximity to the inner longitudinal edge of the strip 2 when said returned portion 7 is compressed to hold the door D closed, as is believed to be clearly illustrated in Fig. 2.

The returned portion 7 at a predetermined point inwardly of its free end is provided with the transversely disposed offset 8 which affords a shoulder adapted to engage the outer edge or face of the door D, and whereby said door is held in closed position. This action is further facilitated in view of the fact that the returned portion 7 possesses a certain degree of inherent resiliency when the free end portion thereof is constantly urged toward the door D when said door D is in contact therewith. It is also to be noted that the offset portion 8 is on such an incline as to readily permit the door being forced open without material interference.

It has also been found of importance to have the bend 6 offset laterally and in a direction away from the returned portion 7 so that said returned portion 7 intermediate the bend 6 and the offset 8 is free and unobstructed.

From the foregoing description, it is thought to be obvious that a door fastener constructed in accordance with our invention is of an extremely simple and comparatively inexpensive nature and is particularly well adapted for use by reason of the convenience and facility with which it may be assembled, and it will also be obvious that our invention is susceptible of some change and modification without material departure from the principles and spirit thereof and for this reason we do not wish to be understood as limiting ourselves to the precise arrangement and formation of the several parts herein shown in carrying out our invention in practice, except as hereinafter claimed.

We claim:

A device of the character described comprising a plate provided with a lateral extension, said extension having its free end

portion returned, said returned portion at a predetermined point inwardly of its free end being offset transversely to afford a shoulder, said returned portion being resilient, said returned portion intermediate the shoulder and the free end thereof being free and unobstructed, the bend connecting the extension and the returned portion thereof being offset laterally and 10 in a direction away from the returned portion so that said returned portion interme-

diate the bend and the shoulder is also free and unobstructed.

In testimony whereof we hereunto affix our signatures in the presence of two witnesses.

MATHEW P. EMBACH.
JOHN L. BRUCE.

Witnesses:

J. ROSS BAILEY,
J. L. SKINNER.
